Primary Examiner — April Rivas

(57) **CLAIM**

The ornamental design for a carry bag for earphones, as shown and described.

DESCRIPTION

FIG. 1 is a perspective view of a carry bag for earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the carry bag for earphones where the carry bag for earphones is in a configuration of use.

The broken lines in FIG. 9 showing a band depict environment and form no part of the claimed design. The other broken lines in the drawings depict portions of the carry bag for earphones that form no part of the claimed design.

1 Claim, 9 Drawing Sheets
